UNITED STATES PATENT OFFICE.

CHARLES C. OATEY, OF DUBUQUE, IOWA.

ELECTRIC CLEANING DEVICE.

Application filed August 11, 1921. Serial No. 491,540.

To all whom it may concern:

Be it known that I, CHARLES C. OATEY, a citizen of the United States, residing at Dubuque, in the county of Dubuque, State of Iowa, have invented certain new and useful Improvements in Electric Cleaning Devices; and I do hereby declare the following to be a full, clear, and exact description of the invention, such as will enable others skilled in the art to which it appertains to make and use the same.

This invention relates to new and useful improvements in cleaning machines and particularly to machines for cleaning meat chopping-blocks, floors, or for sand-papering or dusting other surfaces.

One object of the invention is to provide a device of this character which has an electrically driven cleaning element, the device being arranged to be pushed over the floor, chopping-block, or other surfaces to be treated.

Another object is to provide a device of this character which includes a dusting element arranged to be connected with the drive shaft and the brush of the dusting element moved over the surface to be cleaned.

Another object is to provide a device of this character which includes means for feeding a liquid to the surface to be cleaned, and to the cleaning brush, so that the surface can be more efficiently cleaned, the material removed from the surface being thrown into a receptacle which is readily removable for emptying or destruction and replacement by a new one.

Other objects and advantages will be apparent from the following description when taken in connection with the accompanying drawing.

In the drawing:

Figure 1 is a side elevation of a cleaning machine made in accordance with the invention.

Figure 2 is a bottom plan view of the same.

Figure 3 is a vertical longitudinal central sectional view on the line 3-3 of Figure 2.

Figure 4 is a horizontal longitudinal sectional view taken on the line 4-4 of Figure 3-3, above the motor and brush, and through the liquid receptacle.

Figure 5 is a vertical longitudinal sectional view on the line 5-5 of Figure 4, outwardly of the worm shaft.

Figure 6 is an enlarged central sectional view showing the brush and the shaft mounting.

Figure 7 is an elevation of the duster attachment partly in section.

Referring particularly to the accompanying drawing, 10 represents a housing of suitable size and shape, and which is provided with a bottom wall 10' having an opening 11' formed therein. In the rear portion of the housing 10, and supported by suitable brackets 11, is an electric motor 12, having its shaft 13 extending transversely of the housing and provided with a bevel gear 14 on the outer end. In the forward portion of the housing, and at opposite sides thereof, are the socket bearings 15 and 16, which support the internally threaded members 17 and 18, respectively. Removably screwed into the members 17 and 18 are the externally threaded ends of the brush shaft 19. The member 17 has a worm gear 20 which meshes with a worm shaft 21, extending longitudinally in the housing 10, and supported in the brackets 22. One end of the worm shaft 21 has a bevel gear 23 which meshes with the bevel gear 14 of the motor shaft. The outer end of the member 18 is disposed through an opening in the side of the housing and is externally threaded for a purpose which will presently appear. On the side of the housing, surrounding the said opening, is a threaded flange 24 onto which is screwed a cap 25 for protecting the end of the member 18, when the same is not being used with the duster which will be later referred to.

Carried by the housing and extending longitudinally underneath the bottom thereof, are the runners 26, which serve to support the device in its movement over the article being cleaned. These runners are detachably secured at their forward ends to the housing by means of the set screws 30, while they are connected at their rear ends by means of the bolts 47 which pass loosely through openings in the lugs 28 and which are threaded within openings formed in the runners, as shown at 48. Disposed between the lugs 28 and the runners and encircling the bolts 47 are the springs 49, which normally urge the housing and the runners apart. The supporting runners are slightly longer than the housing and the forward ends thereof overlap the lower portion of the housing. The forward portions of the

runners 26 are cut away to form an opening 26' which opening registers with the opening 11' formed in the bottom of the housing and through which the bristles of the brush 19 project for action upon the surface to be treated. Hinged at the rear end of the housing is a door 31 which is arranged to close an opening 32 in the side wall of the housing, suitable fastening means 33 being provided on the door and housing for holding the door in closed position. Within the housing, directly inwardly of the opening 32, is a metal receptacle 34 having its forward end open and having disposed therewithin a removable paper or fiber container 35, the open end of which is disposed in the open end of the receptacle. Carried by the lower side of the open end of the receptacle is a downwardly and forwardly extending scoop blade 36, the same being in position to direct the material from the brush into the container. Secured to the lower face of the forward end of the bottom wall 26 are the surface engaging rollers or casters 37.

Mounted in the housing, above the brush 19, is a liquid container 38, the lower end of which is formed with a discharge spout 39 for delivering liquid to the brush.

30 Detachably connected to the sides of the housing 10 are the upwardly and rearwardly extending bars 40, the upper ends of which are connected by the handle bar 41, which is grasped by the operator to push the machine over the surface to be cleaned.

Adapted to be screwed onto the outer end of the member 18, when the cap 25 is removed, is the threaded socket 42 of one end of a flexible shaft 43. The other end of the 40 shaft is arranged to be detachably secured in the socket 44 of the dusting brush 45, as clearly seen in Figure 7 of the drawings.

Carried by the upper side of the housing are the handles 46 which are adapted to be 45 grasped by the operator when moving the device over the surface of a meat chopping-block.

What is claimed is:

1. A cleaning device including a housing, 50 detachable supporting runners carried by the housing and formed to provide an opening, a brush mounted within the housing and operating through the opening, and means for normally urging the runners and housing apart.

2. A cleaning device including a housing, one end of the bottom of which is located above the plane of the other end, the said housing being provided with an opening in 60 the lower end of the bottom, detachable supporting runners carried by the housing and formed to provide an opening registering with the opening in the housing, and a brush mounted within the housing and operating through the openings.

3. A cleaning device including a housing, having one end portion thereof located above the plane of the other end, the lower end of the housing having an opening therein, and a slanting portion extending between the 70 higher end and the lower end, detachable supporting runners carried by the housing and formed to provide an opening registering with the first opening, and a brush mounted within the housing and operating 75 through the openings.

4. A cleaning device including a housing having one end portion thereof located above the plane of the other end, the bottom of said housing being formed with an opening 80 and provided with a scoop adjacent the opening, and detachable supporting runners carried by the housing.

5. A cleaning device including a housing having an opening in the bottom thereof, 85 and a scoop positioned adjacent the opening, detachable supporting runners carried by the housing, means for normally urging the runners and housing apart, and a brush mounted within the housing.

6. A cleaning device including a housing having one end portion thereof located above the plane of the other end, the lower end of the housing having an opening therein, and a slanting portion extending between the 95 higher end and the lower end to form a scoop, detachable supporting runners carried by and covering the bottom of the housing, and formed to provide an opening therein, means for normally urging the runners against the article being cleaned, and a brush mounted within the housing and operating 100 through the openings.

7. A cleaning device including a housing, 105 detachable supporting runners carried by the housing, the forward ends of the runners being held spaced from the element being cleaned, means for normally urging the rear ends of the runners into engagement with the element being cleaned, and a brush within the housing and operating through the opening.

8. A cleaning device including a housing, supporting runners carried by the housing and formed to provide an opening therein, a motor driven brush within the housing and operating through the opening, and spring means for normally urging the rear portions of the housing and runners apart.

9. A cleaning device including a housing, 120 supporting runners carried by the housing and formed to provide an opening therein, the forward ends of the runners overlapping the lower portion of the forward end of the housing, means carried by the overlapping portions for securing the runners to the housing, lugs carried by the rear end of the housing, bolts passing through the lugs and threaded within openings in the rear ends of the runners, a spring interposed between 125 130

each lug and the corresponding runner and encircling the bolt, and a motor driven brush within the housing and operating through the opening.

5. 10. A cleaning device including a housing having one end portion of the bottom thereof located above the plane of the other end, the higher end forming a dust receptacle, the bottom of the housing slanting from the 10 higher end to the lower end to form a scoop.

detachable supporting runners on the housing formed to provide an opening, and a brush in the housing and operating through the opening.

In testimony whereof, I affix my signature, 15 in the presence of two witnesses.

CHARLES C. OATEY.
